THERMAL SEALING MACHINE

Harry F. Waters, New York, N. Y.

Application July 20, 1940, Serial No. 346,516

10 Claims. (Cl. 93—8)

This invention relates to thermal sealing machines and provides improvements therein.

The present invention provides a special machine for making bags. It provides a machine which when used in a particular manner upon a folded sheet of suitable material forms at one operation two seams at the marginal portions of a folded sheet along two opposite sides, thereby in conjunction with the fold, producing a bag closed at three sides and open at one end.

The sheet material for forming the bag may be a sheet of thermoplastic material, as for example pliofilm, or of another material as paper lined with or having a strip or band of a thermoplastic substance or adhesive at the place where the seam is to be made. Sheets of cellulose ester material, vinyl resin material, or of paper coated therewith, are examples of other sheet material.

The invention further provides a sealing machine and method capable of producing two seams at the marginal portions at two sides of a folded sheet, for forming a bag having a special assembly within a folded piece of cardboard or the like for forming a carton or case, said two seams, in conjunction with the fold in the bag-forming-sheet forming the bag at one operation.

The invention further provides a machine of the character described capable of ready adjustment for forming bags of different sizes.

The invention further provides a machine which is capable of producing parallel seams of substantially uniform strength throughout, durable and tight throughout. The performance of the machine is such that a bag formed from a folded sheet of thermoplastic material, such as pliofilm or a folded sheet of paper lined or striped with a thermoplastic material is tight at the seam so as to reliably confine its contents, including liquids and gases.

An embodiment of the invention is illustrated in the accompanying drawings, wherein:

Fig. 1 is a top plan view of the said embodiment.

Fig. 2 is a front elevation of the machine shown in Fig. 1.

Fig. 3 is a detail view, partly in front elevation and partly in vertical section, of certain parts including the sealing bar and backing member, shown in Fig. 2.

Fig. 4 is a detail view, partly in top plan and partly broken away to show underlying parts, of the work-support shown in Fig. 1.

Fig. 5 is an enlarged detail view, partly in front elevation and partly in vertical section, of the 55

sealing bar and its means of connection to the head which carries it.

Fig. 6 is a top plan view, broken away in certain parts, of a folded bag-forming sheet assembled within a folded carton blank, and showing one type of work on which the machine is designed to operate.

Referring to said drawings, numeral 10 designates a base or table having therein a way 11, 10 which, in the example shown, may be a surface of the bed or table between opposite flanges 12 and 13. On the ways 11 are two complete sealing units 15, 16. These two sealing units 15 and 16 are advantageously identical and are arranged 15 on the ways in reverse position. The units 15, and 16 are movable along the ways, to adjust the distance separating them to adapt them for forming seams at different distances apart. The two units may be fixed on the ways by clamping 20 bars 18, attached to the bed 10 and overhanging a part of the base of each unit, or in any other suitable manner.

The sealing units 15 and 16 comprise sealing bars 20, 21, and platens or backing members 23, 25 24, one on each unit, those on one unit being parallel to those on the other. The sealing bars 20, 21, are heated in a suitable manner, as by means of electrical resistance cartridges 21, 28, embedded in the sealing bars.

30 The sealing bars 20, 21, are reciprocated toward and from the backing members 23, 24, to press and heat thermoplastic of or on a folded sheet between the sealing bars and backing members, to form a seam.

35 The sealing bars 20, 21, are reciprocated toward and from the backing members 23, 24, by suitable means which advantageously comprise electric motors 30, 31. The sealing bars 20, 21, are attached to elongated heads 33, 34. Each of

40 these heads 33, 34, as here shown, may be mounted on arms 36, 37, extending from a rock shaft, or sleeve, 38, 39. The rotary motion of the motors 30, 31, may be translated to rocking movement of the shafts 38, 39, through speed reducing gears 41, 42, shafts 43, 44, cams 46, 47, and cam riding arms 48, 49. Ordinarily, the sleeves of the cams 46, 47, are connected to the shafts 43, 44, through clutches, a type of clutch including latches 51, 52, being shown. The clutch operating means on each unit comprises a pivoted arm 53, 54, having an inclined portion 55, 57, normally resting in a position to turn the latch to disconnect the cam and its sleeve from the shaft 43, 44. The pivoted lever 53, 54, is turned upward out of position to contact with the latch

45

50

51, 52 (and thereby bring about a driving connection of the cam 46, 47 with the motor driven shaft 43, 44), which turning may be effected by means of a lever 60, 61, having a pin 63, 64, engaging the tail of the lever 53, 54, and pull-rods 66, 67, connected to levers 60, 61.

Means are provided for simultaneously actuating the clutches 51, 52, to actuate the sealing bars 20, 21, to simultaneously produce seams. This simultaneous clutch actuating means comprises a bell-crank lever 70 having arms 71, 72. Arm 71 is fastened to treadle-bar 73, and to the arm 72 is pivotally connected a block 74. An equalizing bar 75 is pivotally attached at its mid-portion to the block 74 as by means of a pivot-pin 77 on the block. The pull-rods 66, 67, of the clutch operating mechanism are attached to levers 80, 81, which levers are pivoted at opposite ends with relation one to the other, as indicated at 83, 84. A push on the foot treadle acts to connect the cams 46, 47, to the motor driven shafts 43, 44, through the equalizing bar 75, levers 80, 81, pulled-rods 66, 67, levers 60, 61, pivoted arms 53, 54, and latches 51, 52.

The connection between the sealing bars 20, 21, and the heads 33, 34, is such that a flush contact is obtained between the work-contacting faces 85 of the sealing bars and a folded sheet lying between these and the backing members 23, 24, the connection being advantageously such as to allow a certain accommodation of the sealing bars 20, 21, to such a flat work-contacting position with relation to the heads 33, 34. The connection may be designated as a floating connection. Said floating connection may comprise tie-bolts 90, 91, 92, 93, attached to the sealing bars 20, 21, the tie-bolts 90, 91 passing through tapered slots in the head 33, and the tie-bolts 93, 94 passing through similar slots in the head 34. The taper allows a limited amount of rocking of the sealing bars 20, 21, laterally with relation to the heads 33, 34.

The tie-bolts 90, 91 are tensioned by means of resilient means extending longitudinally of the head 33, and acting in compression between the head 33 and the sealing bar 20. The tie-bolts 92, 93 are tensioned by similar means. The tensioning means advantageously comprise a plurality of springs 95, 96, etc. arranged longitudinally between the sealing bar 20 and its head 33, and between the sealing bar 21 and its head 34. The compression of the series of springs 95, 96, etc. may be controlled by means of screws 100, 101, 102, 103, 104, 105, to vary, or to equalize, the force of compression of the independent springs. The resilient means between each sealing bar and its head has the effect of exerting a persistent pressure of the sealing bar against the work, at the limit of downward movement of the arms 36 or 37 to which the heads 33, 34 respectively are connected, thus contributing to the formation of a perfect seam. If in the working of the machine, slightly more pressure is desired at one part of the bar than at another, adjustment may be effected through the screws 100 to 105.

The sealing machine is well adapted for forming a bag at a single operation from a special assembly of bag-forming sheet A and carton-forming sheet B in which the fold of the bag-forming sheet is at the bottom edge, as indicated by the letter C, and in which the fold of the carton-forming sheet is also at its bottom, as indicated by the letter D, the folded bag-forming sheet A, being arranged between the

upper and lower portions of the folded carton-forming sheet B, one form of which is illustrated in Fig. 6. In the form of assembly illustrated in Fig. 6, the folded bag-forming sheet A is open at its parallel sides F and G, and the marginal portions thereof at these sides F and G extend laterally beyond the upper portion of the folded carton-forming blank B, in such manner as to give access to the sealing bars 20, 21 at these portions, to form seams K and L. The sealing bars 20, 21 are long enough to cross the fold C of the bag-forming sheet A, and ordinarily extend beyond the bag-forming sheet at its opposite end. The two sealing bars 20, 21 operating simultaneously on such an assembly as illustrated in Fig. 6, form seams K and L, which, in conjunction with the fold C, form at one operation a bag open at one end.

Means are provided for supporting a folded bag-forming sheet, or an assembly of such a sheet with a folded carton blank while the seam is being formed. Each unit 15, 16 is provided with a bracket 106, 107 each of which supports a backing member 23 or 24. Attached to these brackets are bars 110, 111. Supported on the bars 110, 111 are plates 113, 114, which extend in front of the sealing bars, and run on the outside thereof parallel therewith, and constitute a support for the work intermediate the parallel sealing bars and backing members 20, 23 and 21, 24. The sealing units 15, 16 are adjustable in the way 11, as previously described, and the work-supporting plates 113, 114 move with their respective units when the distance between the sealing bars is adjusted for bags of different width by movement of the said sealing units 15, 16 in the way 11. The work-support plates 113, 114, advantageously have an adjustment independent of that of the sealing units 15, 16. To this end the supporting bars 110, 111, may be slotted, as indicated at 116, 117, Fig. 4, and the work-support plates 113, 114 fastened to the bar supports 110, 111 by screw bolts 118, 119 which pass through said slots 116, 117. By loosening the screw bolts 118, 119, the work-supporting plates 113, 114 may be adjusted to increase or decrease the space between them independently of the adjustment of the sealing units 15, 16, in the way 11.

Guide rails 121, 122, may be provided. These are attached to the work-support plates 113, 114, and run parallel with the sealing bars 20, 21. These, like the work-support plates 113, 114, are adjustable with the sealing units 115, 116 by which they are carried. These guide rails 121, 122 are advantageously given an independent adjustment. They may be slotted, as indicated at 125, 126, and screws 127, 128 pass through these slots into the plates 113, 114. By loosening the screws 127, 128, the guide rails 121, 122, may be shifted toward or from the sealing bars 20, 21, to bring the marginal portions of a folded bag-forming sheet A, or such a folded sheet assembled with a folded carton blank, into proper position between the respective sealing bars and backing members 20, 23 and 21, 24 to be properly seamed.

Operation

A folded bag-forming sheet A, or such a sheet assembled with a folded carton-forming sheet B as illustrated in Fig. 6, is placed on the work-support which comprises in part the plates 113, 114. Previously the sealing units 15, 16, are adjusted in the way 11 to bring the sealing bars 20, 21, in proper position, for the size of sheet

to be formed into a bag, for the sealing bars 20, 21 to contact with the marginal portions F, G, at which the seams are to be formed. If additional support is required between the sealing bars 20, 21, the work-support plates 113, 114, are moved outwardly on the supporting bars 110, 111, first loosening and then tightening the bolts 118, 119. The under part of a folded carton blank B may extend laterally beyond the marginal portions F and G of the folded bag-forming bag A, in which circumstance the guide rails 121, 122, are moved apart so that they will act on the side edges of the carton-blank with the marginal portions F and G of the bag-forming blank in proper position to be seamed by the sealing bars 20, 21. The adjustment of the guide rails 121, 122 is effected through the screws 127, 128, and the slots 125, 126 in the guide rails.

With the folded bag-forming sheet A, or with the assembly of such a sheet with a folded carton-forming sheet B, in position on the work-support, and with the ends of the sealing bars 20, 21, extending over the fold C of the folded bag-forming sheet A, the foot treadle 13 is pushed away from the operator, swinging the arm 72 of the bell-crank lever down, and carrying with it the equalizing bar 75. The equalizing bar at its ends, pulls down the oppositely pivoted levers 80, 81, and these pull on the pull-rods 66, 67, which are attached to the levers 60, 61, which levers carry the pins 63, 64 which bear on the levers 53, 54 and move the latch-contacting portions 56, 57 thereof out of contact with said latches. This allows the latches 51, 52, to engage the shafts 43, 44, and thereby clutch the cams 46, 47, to said shafts 43, 44, which are driven by the motors 30, 31. The cams 46, 47, acting on the arms 48, 49, of the rock-shafts 38, 39, turn the said rock-shafts 38, 39, and move the heads 33, 34 (carried by the arms 36, 37, attached to said rock-shafts) toward the folded bag-forming sheet lying on the work-support with its marginal portions extending over the backing members 23, 24. The heads 33, 34, to which the sealing bars 20, 21 are connected by a floating connection, press the sealing bars against the marginal portions F and G of the bag-forming sheet A. The downward movement of the heads 33, 34 continues slightly beyond the point where the sealing bars make contact with the bag-forming sheet, so as to additionally tension the resilient means comprising the compression springs 95, 96. The cams 46, 47 by reason of their contour, maintain the heads 33, 34, at their lowermost position through a certain interval of time. During this time the margins of the bag-forming sheet are under the pressure of the springs 95, 96, etc. and are also subject to the heat of the sealing bar. While thus under pressure and heat, the thermoplastic material of which the bag-forming sheet is made, or lined, or striped at the place of seal, softens and welds to form the seam. By reason of the floating connection between the sealing bars 20, 21, and their heads, the work-contacting faces 85 of the sealing bars can adjust or accommodate themselves to the flat surface of the material, and thereby form a weld or joint of equal strength and security the full width of the aforesaid work-contacting faces 85 of the sealing bars.

When the arms 48, 49, respectively of the rock-shafts 38, 39, to which the heads 33, 34 are connected, ride off of the high part of the cams, springs 130, 131 move or reciprocate the

sealing bars 20, 21, away from the work, and, within the interval preceding the next downward movement of the sealing bars, the work is removed and replaced by a new piece.

The reciprocation of the heads 33, 34, and of the sealing bars 20, 21 carried thereby, is simultaneously stopped by removing the foot from the treadle 13.

By the operation of the machine, as described, 10 a specially folded bag-forming sheet, or such a sheet in a special assembly with a folded carton-forming sheet as illustrated in Fig. 6, is simultaneously seamed at its two marginal portions F and G, and a bag which is seamed at its two sides by the seams K and L, closed at its bottom by the fold C, and open at the top, is formed at one operation of the machine.

The invention may receive other embodiments than that herein specifically illustrated and described.

What is claimed is:

1. In a heat sealing machine, the combination which comprises a pair of sealing units, each of said units including a sealing bar and heating means and a backing member for said bar, means for individually and independently displacing said units with the sealing bars in parallel spaced position with respect to each other to adjust the distance between the sealing bars of said units, and means for simultaneously actuating said units to apply heat and pressure to two parallel marginal strips of a sheet bearing fusible material in one operation.

2. In a heat sealing machine, the combination which comprises a pair of sealing units; each of said units including a sealing bar, heating means for said bar, a backing member for said bar, and an actuating mechanism for said bar to move the bar from an inoperative into an operative and heat sealing position; means for independently displacing said units to adjust the distance between their respective sealing bars, means for fixing said units in such adjusted position; and means in common for both of said units for simultaneously initiating the operation of both units.

3. In a heat sealing machine, the combination which comprises a pair of displaceable sealing units; each of said units including a sealing bar, heating means and a backing member for said bar, an actuating mechanism for said bar adapted when actuated to apply the sealing bar against a sheet interposed between the bar and the backing member, driving means for said actuating mechanism, and means intermediate to said driving means and said actuating mechanism to maintain them normally disconnected; and means in common for both of said units operable independently from the relative positions of the units to simultaneously connect the driving means of each unit to its corresponding actuating mechanism.

4. In a heat sealing machine, the combination which comprises a pair of sealing units; each of said units including a heated sealing bar, a backing member adapted to cooperate with said bar, the sealing bars of said units being arranged in parallel-spaced position, an actuating mechanism for said bar, driving means for said actuating mechanism, and a clutch intermediate to said driving means and said actuating mechanism; means for individually and independently displacing said units to adjust the space between their respective sealing bars; and means in common for both units to cause simultaneous

operation of the clutch in each unit whereby said sealing bars will be moved against the corresponding backing members to form parallel seams upon a fusible sheet interposed between the bars and the backing members.

5. A thermal sealing machine comprising a pair of sealing units, a common bed for said units, aligned ways on said bed on which said sealing units are seated in opposite relationship, and on which ways said units may be moved toward and from one another to vary the space between the units, each of said units comprising a sealing bar, a means for heating the same, and a platen or backing member, the sealing bar and backing member on one unit being arranged parallel to those on the other unit, and means for simultaneously actuating said sealing bars to press and heat marginal portions of a folded sheet between the sealing bars and the backing members, to form parallel seams at opposite sides of a sheet.

6. A thermal sealing machine comprising a pair of sealing units, a common bed for said units, aligned ways on said bed on which said sealing units are seated in opposite relationship, and on which ways said units may be moved toward and from one another to vary the space between the units, each of said units comprising a sealing bar, a means for heating the same, a platen or backing member, means for reciprocating the sealing bar, a motor for driving said reciprocating means and a clutch between said motor and said reciprocating means, the sealing bar and backing member of one unit being arranged parallel to those on the other unit, and means for simultaneously operating said clutches to connect said sealing bar reciprocating means to said motor, to simultaneously actuate said sealing bars, to press and heat the marginal portions of a folded sheet between the sealing bars and the backing members to form parallel seams at opposite sides of a sheet, said clutch operating means comprising a pull-rod as a part of each clutch operating mechanism, a lever connected with each pull-rod, oppositely arranged fulcrums for said levers, an equalizing bar bearing on each of said levers, a movable support having a

5 pivotal connection to the middle portion of said equalizing bar, and means for moving said movable part equalizing bar, levers and pull-rods to simultaneously connect the motors through said clutches to each of said sealing bar reciprocating means.

7. A thermal sealing machine according to claim 5, wherein each sealing unit further comprises a work-support running parallel with the backing member, said work-support being mounted on its unit, and adjustable with its unit on said ways toward and from the corresponding work-support on the opposite unit.

8. A thermal sealing machine according to claim 5, wherein each sealing unit further comprises a work-support running parallel with the backing member, said work-support being mounted on its unit, and adjustable with its unit on said ways toward and from the corresponding work-support in the opposite unit, and means for adjusting said work-support laterally with relation to the backing member of its unit.

9. A thermal sealing machine according to claim 5, wherein each sealing unit further comprises a work-support running parallel with the backing member, said work-support being mounted on its unit, and adjustable with its unit on said ways toward and from the corresponding work support on the opposite unit, and a guide rail mounted on said work-support, parallel to said backing member.

10. A thermal sealing machine according to claim 5, wherein each sealing unit further comprises a work-support running parallel with the backing member, said work-support being mounted on its unit, and adjustable with its unit on said ways toward and from the corresponding work-support on the opposite unit, means for adjusting said work-support laterally with relation to the backing member of its unit, a guide rail mounted on said work-support parallel to said backing member, and means for adjusting said guide rail on said work-support laterally of said backing member.

HARRY F. WATERS.
